UNITED STATES PATENT OFFICE.

WILLIAM S. SYLVESTER, OF DENVER, COLORADO.

SPRING OILER.

Application filed September 11, 1923. Serial No. 662,056.

To all whom it may concern:

Be it known that I, WILLIAM S. SYLVESTER, a citizen of the United States, residing at Denver, in the city and county of Denver, 5 and State of Colorado, have invented certain new and useful Improvements in Spring Oilers; and I do declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to a device for oiling automobile springs.

Springs, such as are ordinarily employed in connection with automobiles and other types of vehicles, are almost invariably 20 formed from a plurality of springs assembled in superposed relation with each leaf shorter than the adjacent longer leaf. Such a spring is usually designated as a multiple leaf spring and owes its flexibility to the nature 25 of the material employed and to the fact that the several leaves have a sliding motion with respect to each other. If the several leaves were connected in such a manner that they were not relatively slidable, then the 30 spring would be stiff and unyielding, being in effect a solid bar of steel. In order that a multiple leaf spring shall function properly, the leaves must be freely slid able and this they can only do by being properly lubricated. It is difficult to lubricate a multiple 35 leaf spring and for that reason very few springs receive any lubrication whatever and finally rust and become inoperative and unsatisfactory.

40 It is the object of this invention to produce a simple device that can be cheaply made and readily applied to any multiple leaf spring, and which will keep the spring properly lubricated at all times.

45 My invention can be most clearly explained by reference to the accompanying drawing in which the preferred embodiment thereof is shown, and in which:

Fig. 1 shows a side elevation of an elliptical spring to which my improved oiler has 50 been applied;

Fig. 2 is a section taken on line 2—2, Fig. 53; and

Fig. 3 is a section taken on line 3—3, 55 Fig. 2.

The same reference characters will be employed to designate the same parts throughout the several views.

Numeral 1 designates the upper half and 2 the lower half of an elliptical multiple leaf spring. Each half has a master leaf 3 and a plurality of auxiliary leaves 4 which are progressively shorter than the master leaf. The several leaves are held together by clamps 5 and sometimes by central bolts 60 (not shown). At various points along the spring there are clamps 6 which hold the leaves in alignment. My improved oiler consists of a member 7 of sheet metal bent into channel shape in the manner shown in 65 Fig. 3. The sides 8 are slightly wider than the thickness of the spring at the point where they are applied and are perforated for the reception of a clamping bolt 9. The length of the oiler may be determined by the 70 construction of the spring to which it is applied, but is preferably four inches. Extending transversely through the oiler near the bottom portion thereof is a flattened tubular member 10 which has its narrow sides 75 80 perforated in the manner indicated by numerals 11. The flattened member 10 is formed from a pipe, a portion 12 of which is left circular and extends diagonally from the oiler in the manner clearly shown in 85 Fig. 3. A spring oil cap 13 is secured to the end of the pipe 12 and serves to exclude the dust and dirt. A piece of thick rubbing felt 14 is placed in the bottom of the oiler and rests upon the spring when the oiler is in 90 place thereon. Extending from one end of the bottom portion 7 is a projection 15 which is adapted to be inserted into the space between the surface of the spring and the inside of the clamp 6 in the manner shown in 95 Fig. 2. This serves to prevent the oiler from sliding along the spring surface. The pipe 12 is usually connected to the oiler near the end of the oiler furthest from the projecting portion 15. When the oilers are applied to 100 the springs they are secured thereto at the highest point to which they can be conveniently connected. On the upper half of the spring the oilers are secured near the center and on the lower half near the ends, 105 all as shown in Fig. 1. The oilers are so constructed and arranged that the pipe 12 is at the highest end of the oiler.

When the oiler is in place on the spring, as shown in Fig. 1, and oil is introduced 110

into the pipe 12, the felt 14 will become saturated with oil and as the spring flexes, some of this oil will be squeezed out and flow down over the sides of the leaves. The oil 5 will penetrate between the leaves, due to the capillary action, and as the oilers are located at the highest point or points of the springs, the oil will flow downwardly between the leaves and thereby keep the entire 10 spring leaf surfaces properly lubricated.

From the above, it will be apparent that I have invented a simple spring oiler that can be applied to any multiple leaf spring and which will keep the same properly lubricated 15 at all times.

Having now described my invention, what I claim as new is:

1. A spring oiler comprising a channel-shaped member of sheet metal, one end of 20 the bottom of said member being longer than the sides, a pipe having one end flattened, said flattened end projecting through the oiler near the bottom thereof, a piece of felt within said member, and means for clamping 25 the member to a spring.

2. A spring oiler comprising in combination, a body member of sheet metal bent into a U-shaped cross-section, said member having a bottom and two sides, a flattened tubular member extending through the body 30 member near the bottom thereof, said tubular member having one end cylindrical, said cylindrical end projecting outwardly from the body member and being angularly inclined with respect to the sides thereof, said 35 cylindrical end being angularly inclined with respect to the sides thereof, said

sides being provided with openings for the reception of a clamping bolt.

3. A spring oiler comprising, in combination, a body member of sheet metal bent into a U-shaped cross-section, said member having a bottom and two sides, a flattened tubular member extending through the body member near the bottom thereof, said tubular member having one end cylindrical, said cylindrical end projecting outwardly 40 from the body member and being angularly inclined with respect to the sides thereof, said sides being provided with openings for the reception of a clamping bolt, the bottom member having one end thereof extending 45 beyond the ends of the sides.

4. A spring oiler comprising, in combination, a body member of sheet metal bent into a U-shaped cross-section, said member having a bottom and two sides, a flattened tubular member extending through the body member near the bottom thereof, said tubular member having one end cylindrical, said cylindrical end projecting outwardly 50 from the body member and being angularly inclined with respect to the sides thereof, said sides being provided with openings for the reception of a clamping bolt, the bottom member having one end thereof extending 55 beyond the ends of the sides, and a piece of absorbent felt in the bottom of said body member.

In testimony whereof I affix my signature.

WILLIAM S. SYLVESTER.
